UNITED STATES PATENT OFFICE.

CLARENCE Z. HUBBELL, OF SPOKANE, WASHINGTON.

WINDOW.

981,858.

Specification of Letters Patent. Patented Jan. 17, 1911.

Application filed September 12, 1908. Serial No. 452,764.

To all whom it may concern:

Be it known that I, CLARENCE Z. HUBBELL, a citizen of the United States, residing at Spokane, in the county of Spokane and State of Washington, have invented new and useful Improvements in Windows, of which the following is a specification, reference being had to the drawings forming a part thereof.

10 The purpose of this invention is to provide a window of an improved construction, of the class in which the sashes are pivoted to hanging stiles so that they may be adapted both to slide vertically and to swing on 15 horizontal pivots.

It consists in the features of construction shown and described as indicated in the claims.

In the drawings:—Figure 1 is a perspective view of a window embodying this invention shown with the lower sash swung into horizontal position. Fig. 2 is a vertical section of the casing and sashes therein, the upper sash being at the lowest position 25 and swung inward, the lower sash being at the highest position. Fig. 3 is a horizontal section through one side of the casing and the upper sash, the lower sash being broken out and shown in section through a securing catch. Fig. 4 is a detail elevation showing the pivotal connection of the sash with the hanging stile. Fig. 5 is a section at the line 5—5 on Fig. 4 the sash being shown at closed position. Fig. 6 is a detail section 35 of the sash side-bar and hanging stile, showing a catch device. Fig. 7 is a perspective view of two parts of such catch device disconnected from each other. Fig. 8 is a detail vertical section of the upper side of the 40 casing showing a slight modification. Fig. 9 is a detail perspective view of one corner of a sash showing a releasable clamping device.

The casing, A, has vertical run-ways for 45 upper and lower sashes in the usual relation to each other for causing the two sashes to lap at their meeting rails, the meeting rail of the lower sash and the customary under-beveled, lip overhanging the reciprocally 50 beveled lip of the meeting rail of the upper sash. The run-ways for the sashes are, more strictly speaking, run-ways for the hanging stiles, said hanging stiles, B, being preferably formed of sheet-metal folded to 55 form a channel between two flanges, B¹, B¹,

and a third flange, B², projecting in the opposite direction, being formed by folding the metal back upon itself at b, the edge of said flange, B², being preferably deflected inward,—that is, toward the sash,—forming a 60 lip, b², resting against the surface of the sash for insuring a weather-tight bearing. For the flanges, B¹, B¹, grooves, A¹, A¹, forming guide-ways or slide-ways, are provided in the casing extending from top to 65 bottom thereof. The excess depth of the channel between the flanges, B¹, B¹, over the depth of the grooves, A¹, A¹, is sufficient to accommodate the suspending chain, C, which runs over pulleys, D, at the top of the 70 casing into the counter-weight pocket, A², of the casing, in which the counter-weights, H, are suspended and run, for retaining the stile with its flanges, B¹, in the grooves, A¹. The forward flange, B¹, has the metal folded 75 back upon itself at the inner edge so as to form a stop shoulder, b¹; and a retaining plate, P, is let into the casing and secured thereto with one edge projecting into the groove, A¹, in front of said shoulder, b¹, as 80 seen clearly in Fig. 3, for retaining the hanging stile, B, in the casing.

Each sash is pivoted to its two hanging stiles near the lower end of both the sash and stile, the pivotal connection being preferably adapted to permit the sash to be disconnected from the stile without removing the stile from the casing; and for this purpose, as well as for the convenient operation of the device in other respects, the form of 90 pivotal connection shown comprises a plate, E, let into the edge of the sash having rigidly projecting headed studs, G, G, which engage the slot, B³, in the web of the hanging stile. This slot B³, commencing a 95 little inward from the outer flange, B¹, of the stile, extends obliquely upward and forward to a point about midway in the width of the stile, and then obliquely downward, opening from the lower edge of said web 100 just inside the outer flange. The preferred course and form of the slot is that shown, in which the upwardly and downwardly trending elements are substantially at right angles to each other, making the slot L-shaped with the right angle at the top. The two studs, G, G, are located so that when the lower one is in the outer end of the slot the other is at the apex or angle of the slot. As 105 the sash is swung pivotally at its con- 110

2
nection with the stile the two studs will be substantially in the same horizontal plane, as shown in full lines in Fig. 4, when the sash is inclined at an angle of 45° , and the inner or lower one will be at the apex of the slot, and the other at the lower end or mouth of the slot, when the sash is at horizontal position. It will be seen that if from this position the sash is moved bodily in an oblique downward and inward direction both studs will travel out of the slot and the sash will thereby be disengaged from the hanging stile, and may be reengaged by reversing the order of movement.

The lower sill, A^4 , of the casing is recessed or cut away in the path of the outer and upper sash, as seen at a^4 , an amount at least equal to, and preferably a little more than the lap of the two sashes at their closed position. The purpose of this is to permit the upper sash to be depressed far enough so that its upper rail will clear the lower rail of the lower sash when the latter sash is at the highest position,—that is, at the top of the casing,—thus permitting the upper sash to be swung inward about its pivotal connection with its hanging stile, so as to be below the lower sash when at such inswing position. This is frequently desirable in use, but is especially designed to make it convenient to wash the upper sash, the inswing horizontal position being the position at which the sash is desirably situated for washing its outer surface. The desirability of this provision will be manifest upon considering that without it the upper sash could not be swung to the described position except with the lower sash also at that position below it, and this would be undesirable and often inconvenient in washing the window. The reason for making the recess, a^4 , more than the lap of the two sashes is to permit the outer and upper sash to be provided with a seat in the head or upper end of the casing behind the stop bar, A^5 , and avoid recessing the stop bar to permit the lower sash to pass to the same height as the outer or upper sash. The thickness of the stop bar and the depth of the recess which receives the upper end of the upper sash at closed position is therefore preferably added to the lap of the sashes to make the full depth of the recess, a^4 , in the lower sill. If preferred, or convenient in any case to construct the head of the casing so as to permit both sashes to pass up to the same point, the depth of the recess, a^4 , need be only the amount of the lap of the two sashes. Such construction is shown in Fig. 8, a mere parting bead, a^6 , being left projecting from the upper stop bar between the paths of the two sashes.

For checking either or both sashes at horizontal position they may be provided with folding checks, K , K , each comprising two

members pivoted together and pivotally connected, one to the edge of the sash and the other to the hanging stile. This device is shown applied only to the lower sash, but it will be readily understood that its use is not limited to this sash.

For locking either sash at closed position there may be provided a two-part device, one part, M , being mounted in the side rail of the sash, and the other part, N , upon the face of the stile, the former being mounted for turning to engage the latter. As illustrated, the part, N , on the stile is a hook-edged angle clip, of which one hooked arm juts off into the path of the sash, and as the sash swings to closed position is received in a recess, m , in the edge of the sash rail opening at the rear side thereof. The part, M , is a short cylinder having a hooked tooth or finger, m^1 , which is turned into engagement with the hooked off-jutting arm of the clip, N^1 , the hook terminal, m^1 , engaging the sloping hook terminal, n^1 , of the part, N , for drawing the hanging stile close against the edge of the sash, and at the same time drawing and holding the sash against the guard lip, B^2 . The cylinder, M , is lodged in a recess in the edge of the sash and engaged and retained therein by the squared end of a spindle, M^2 , which is inserted through a hole bored in from the face of the sash rail, its outer squared end being accessible for operation by a suitable key.

1 claim:

1. In combination with a window casing, a hanging stile and a sash pivotally connected thereto near the lower end of the stile, the pivotal connection comprising two studs projecting from the edge of the sash, the stile having an L-shaped slot with which said studs engage, such slot opening through the edge of the stile to permit the studs to be withdrawn therefrom.

2. In combination with a window casing, a hanging stile mounted for sliding therein and a sash pivotally connected to the stile, the pivotal connection comprising two studs jutting from the edge of the sash, the stile having a slot extending upwardly and inwardly from its commencement near the outer side, and then downwardly and inwardly, and at its inner end opening through the edge of the stile, the two studs being spaced for engagement with the slot, one at the inner and lower end and the other at the apex or crest when the sash is at closed position.

3. In combination with a window casing and upper and lower sashes therein, hanging stiles for the sashes respectively, consisting of channel bars having the channel flanges facing outwardly from the edges of the sashes, one of said flanges being reflexed upon itself to form an inwardly facing stop

shoulder, the casing having grooves forming separate run-ways for the channel flanges, and a retaining plate mounted on the casing intermediate the grooves, projecting into 5 the groove which accommodates the reflexed flange for engaging said shoulder thereof.

4. In combination with a window casing and sash therein, hanging stiles for the sash consisting of channel-bars having their 10 channel flanges facing outwardly from the sash, the casing having grooves forming separate run-ways for the channel-flanges, the sash being pivotally connected to the stiles at the lower edge of the sash, and 15 pivotal connections comprising a slot in the channel bar stile extending across the width of the channel bar between the flanges.

5. In combination with a window casing and sash therein, hanging stiles for the sash 20 consisting of channel-bars having their flanges facing outwardly from the sash, the web of the channel-bar being pivoted to the edge of the sash near the lower side of the latter and lower end of the sash, the pivot 25 connections comprising a stud projecting from the sash engaging a slot which extends transversely in the web of the channel bar between the flanges thereof and which opens through the lower edge of said web for with-

drawal of the stud to disengage the sash 30 from the stiles.

6. In combination with a window casing and sash therein, hanging stiles for the sash consisting of channel-bars having their 35 channel flanges facing outwardly from the edges of the sash, the casing having grooves forming separate run-ways for the separate flanges, one of said flanges being reflexed upon itself to form an inwardly facing stop 40 shoulder; a retaining face mounted on the casing intermediate the grooves projecting into the groove which accommodates the reflexed flange for engaging said shoulder thereof, the sash being pivoted to the stiles, the pivotal connection comprising a stud 45 projecting from the edge of the sash into a slot which extends transversely in the web of a channel-bar, and which opens through an edge of the channel bar for withdrawal 50 and insertion of the stud.

In testimony whereof, I have hereunto set my hand, in the presence of two witnesses, at Spokane, Wash., this 5th day of September, 1908.

CLARENCE Z. HUBBELL.
